UNITED STATES PATENT OFFICE.

WILLIAM F. MARTIN, OF WORMLEYSBURG, PENNSYLVANIA.

COAL SCREENING AND WASHING MACHINE.

Application filed May 13, 1922. Serial No. 561,978.

To all whom it may concern:

Be it known that I, WILLIAM F. MARTIN, a citizen of the United States, residing at Wormleysburg, in the county of Dauphin 5 and State of Pennsylvania, have invented certain new and useful Improvements in Coal Screening and Washing Machines; and I do declare the following to be a full, clear, and exact description of the invention, such 10 as will enable others skilled in the art to which it appertains to make and use the same.

My invention relates to screening devices for coal, ore, and the like and the present 15 disclosure has reference more particularly to screening machines in which the material to be screened is fed to the screening machine with a stream of water. A machine of this character was patented by me on April 11th, 20 1922, No. 1,412,291 and whereas this machine has been highly advantageous in performing certain screening operations, it is the principal object of the present invention to improve upon the construction of the patented 25 machine, by providing means for continually pulsating the movable sides of the several pockets which receive the waste material washed through the screen. By thus pulsating the pocket sides, the waste material and 30 water flowing into the pockets, is continually agitated so that whenever the pockets are in open position, they will fully discharge their contents, thereby preventing any undesirable accumulation which has 35 been found to occur when screening certain forms of materials with the patented machine.

In carrying out the above end, a further 40 aim of the invention is to operate the pulsating means for the pocket sides by a water wheel driven from the water which is discharged through the screen, whereby no additional expense need be entailed for power. It will be understood however that my 45 invention is not restricted to the use of a water wheel to furnish the power for pulsating the pocket sides.

With the foregoing in view, the invention resides in the novel subject matter herein- 50 after described and claimed, the description being supplemented by the accompanying drawings.

Figure 1 is a side elevation of the improved machine.

55 Figure 2 is a longitudinal sectional view with the pockets in open position.

Figure 3 is a transverse section as indicated by line 3—3 of Fig. 1.

Figure 4 is a duplicate of Fig. 2 with the exception that it illustrates the pockets in 60 closed position.

Figure 5 is a top plan view.

In the drawings above briefly described, the numeral 1 designates a suitable frame which is preferably inclined as shown. A 65 screen 2 is fixedly mounted in the upper portion of the frame and a plurality of collecting pockets 3 are formed beneath said screen to receive the waste material, said pockets being here shown of V-shape with 70 straight sides, although they might be of other shapes and provided with curved sides if desired. Each pocket is provided with a movable side wall 4 which is by preference pivotally mounted on hinges or the like as 75 indicated at 5. A connecting rod 6 is pivoted at 7 to the lower edges of the movable sides 4 and is connected by a link 8 with an eccentric 9 on a transverse rock shaft 10 which extends across the upper end of the 80 frame 1. This general construction and arrangement is about the same as that shown in Patent 1,412,291 above referred to, but whereas the rock shaft of this patent was provided with a hand-lever, this lever is now 85 eliminated and means are provided for continually oscillating the shaft 10 so that a longitudinal reciprocation of the connecting rod 6 is produced, which movement will alternately open and close the movable pocket 90 sides 4, thereby effectively agitating the contents of said pockets so that they will be readily discharged instead of accumulating.

In the preferred form of construction, one 95 of the ends of the rock shaft 10 is provided with a crank arm 11 which is usually located on the exterior of the frame 1. A pitman rod 12 is connected with the arm 11, preferably by providing a bolt 13 which may be passed through any one of the openings 14 in the crank arm, so that the rocking movement of the shaft 10 may be changed as occasion may require. Moreover, 100 the length of the pitman rod 12 is preferably adjustable by means of an appropriate turnbuckle or the like 15 so that the closing and opening movement of the pocket sides 4 may be controlled, as may be found most advantageous. The pitman rod 12 is adapted to be reciprocated by any appropriate power, but I prefer to connect said 110 pitman rod with an eccentric 16 on the shaft

17 of a water wheel 18, the latter being located beneath the discharge spout 19 which declines from the short bottom 20 of the frame 1. By this arrangement, the water 5 flowing through the screen 2 onto the bottom 20, will flow from the latter through the spout 19 and will thus operate the water wheel 18, so that without added expense, the connections 12, 11, 10, 8 and 6, are operated 10 to continually pulsate the movable sides 4 of the pockets 3.

While any suitable supports may be provided for the shaft 17 and its water wheel 18, I prefer to secure U-shaped frames 21 to 15 the frame 1 as clearly shown in the drawings.

From the foregoing, taken in connection with the accompanying illustration, it will be seen that by pulsating one side of the 20 pockets 3, I have produced a substantial improvement over my patented machine. Since excellent results may be obtained from the details disclosed, they may well be followed, but within the scope of the invention 25 as claimed, numerous minor changes may of course be made.

I claim:

1. A screening machine comprising a frame having a screen, a bottom for the upper 30 end portion of said frame terminating in a discharge spout, collecting pockets beneath said screen each having a movable side, a connecting rod extending beneath said pockets and pivotally connected to the

movable sides thereof, a transverse rock 35 shaft mounted in the frame and having an eccentric connected to said rod, a water wheel rotatably mounted beneath said frame and rotated by water running from said spout, and means for transmitting movement from said water wheel to said rock shaft for rocking said shaft.

2. A screening machine comprising a frame having a screen, collecting pockets beneath said screen each having a movable 45 side, a bottom in part of the frame to receive water running through the screen, a water wheel driven by water running from said bottom, and operating connections between said water wheel and said movable 50 pocket sides for continually pulsating the latter.

3. A screening machine comprising a frame, a screen therein, collecting pockets in the frame beneath the screen each having a pivoted side wall, a connecting rod beneath said pockets pivoted to the pivoted sides thereof, a transverse rock shaft in the frame having an eccentric connected to said connecting rod, a crank arm on said rock 60 shaft, a pitman connected to said crank arm, and a water wheel mounted below the frame and having an eccentric connected with said pitman.

In testimony whereof I have hereunto set 65 my hand.

WILLIAM F. MARTIN.
